ATTORNEY

UNITED STATES PATENT OFFICE

96,403

DESIGN FOR A CURTAIN RETAINER OR SIMILAR ARTICLE

George H. McEntire, Sterling City, Tex.

Application November 19, 1934, Serial No. 54,081

Term of patent 14 years

To all whom it may concern:

Be it known that I, George H. McEntire, a citizen of the United States, residing at Sterling City, in the county of Sterling and State of Texas, have invented a new, original, and ornamental Design for a Curtain Retainer or Similar Article, of which the following is a specification, reference being had to the accompanying drawing, forming a part thereof.

I claim:

The ornamental design for a curtain retainer or similar article, as shown.

GEORGE H. McENTIRE.
